PUSH-BUTTON FOR A REEL

Carl J. Velte, Jr., Parchment, Mich., assignor to Pflueger
Corporation, Akron, Ohio, a corporation of Ohio

Filed Oct. 24, 1967, Ser. No. 9,137

Term of patent 14 years

Int. Cl. D22—06

U.S. Cl. D22—25

Fig. 1

Fig. 2

Fig. 3

Fig. 4

Fig. 5

Fig. 6

FIG. 1 is a side elevational view of the push-button for a reel, showing my new design.

FIG. 2 is a side elevational view showing the push-button for a reel from the other side.

FIG. 3 is a top view of the push-button for a reel.

FIG. 4 is a bottom view of the push-button for a reel.

FIG. 5 is an elevational view taken from the front.

FIG. 6 is an elevational view taken from the rear.

FIG. 7 is a three-quarter perspective view of the rear side thereof.

FIG. 8 is a three-quarter perspective view taken from the front and slightly below.

FIG. 9 is a perspective view as viewed from the upper left thereof, and

FIG. 10 is a three-quarter perspective view taken substantially from the top thereof.

The essential features of my design reside in the parts shown in solid lines.

I claim:

The ornamental design for a push-button for a reel, substantially as shown and described.
